UNITED STATES PATENT OFFICE.

LEONTINA GULLY, OF UVALDE, TEXAS.

SHAM-BOLSTER FRAME.

SPECIFICATION forming part of Letters Patent No. 691,134, dated January 14, 1902.

Application filed July 9, 1901. Serial No. 67,670. (No model.)

To all whom it may concern:

Be it known that I, LEONTINA GULLY, a citizen of the United States, residing at Uvalde, in the county of Uvalde and State of Texas, 5 have invented a new and useful Sham-Bolster Frame, of which the following is a specification.

This invention relates to sham-bolster frames, and more particularly to that class 10 that are lengthwise adjustable to admit of their being used with beds of any width.

The object of the invention is to provide a cheap, durable, light, and thoroughly-effective device for the purpose in which the parts shall 15 be so constructed and assembled as to permit ready lengthwise adjustment and in which damage to or derangement of the parts in handling will be reduced to a minimum.

A further object is to provide for a thoroughly-efficient holding or assembling of the 20 parts together.

With these and other objects in view the invention consists in the novel construction and combination of parts of the sham-bolster 25 frame, as will be hereinafter fully described and claimed.

In the accompanying drawings, forming a part of the specification, and in which like numerals of reference indicate corresponding 30 parts, I have illustrated a form of embodiment of my invention capable of carrying my ideas into effect, it being understood that the construction and arrangement of parts therein shown may be modified or changed without 35 departing from the spirit of the invention.

In the drawings, Figure 1 is a view in perspective of the bolster-frame, the sections being shown as extended. Fig. 2 is a view in transverse section taken through one of the 40 center bands. Fig. 3 is a view in longitudinal section taken through one of the end bands adjacent to one of the ribs. Fig. 4 is a detail view of a slightly-modified form of center band.

45 In the drawings I have exhibited a bolster-frame composed of two sections 1 and 2, having a telescopic connection with each other; but it is to be understood that I do not limit myself to this number, as more than two sec-

tions may be employed. Each section comprises a plurality of return-bend ribs 3, an end band 4, constituting a rib-retainer, and a center band 5, constituting a combined rib guide and retainer. Each of the ribs 3 is made of a piece of wire of suitable thickness bent upon 50 itself to present a U-shaped structure, the bends of the ribs being disposed toward the center of the frame and the ends being secured in the bands 4, as clearly shown in Fig. 3. The band 4 in this instance is formed by 55 a piece of metal bent longitudinally upon itself to present a recess in which the ends of the ribs are to be housed and is then bent into circular form, as shown in Fig. 1, the ends of the ribs being held between the members 60 of the band by having the band beaded around them, as shown in Fig. 3, or by the employment of solder or by beading and soldering, the object of the beads being to prevent lateral shifting of the ends when once seated between the 65 members of the band. By this manner of assembling the ribs with the band a firm and stable union between the parts will be effected, and as this mode of procedure is one commonly employed for assembling metallic parts to- 70 together, it will be understood that by thus securing the ribs in position there will be no added cost to the device.

75 Each center band 5 comprises two strips of metal 6 and 7, as shown in Fig. 2, the strip 6 constituting the inner side of the band and the strip 7 the outer side. The strip 6 is provided with transverse flutes or beads 8, in which the members of the ribs are designed 80 to work, the strip 7 serving to hold the rib members in the guides, so that when the two sections are assembled to present a band the structure resulting will constitute a combined 85 rib guide and retainer. In assembling the parts of the center band the ribbed or fluted 90 strip is secured to the strip 7 by any suitable means, as by soldering or by riveting or in any other manner. The rib members are then passed through pairs of the guides in alternate order—that is to say, the free ends 95 of one rib-section pointing toward one end of the structure and the ends of the next rib-section pointing in the opposite direction,

and so on throughout the series of ribs, after which the end bands are secured in position in the manner described. Each of the center bands is soldered or otherwise secured to the rib-sections adjacent to the bend, so that these bands will be firmly held in position against shifting on the ribs. In this instance each end band is shown as carrying four ribs, it being understood that this number is merely illustrative and may be increased to any number desired, the space between each pair of ribs of a section being about double that of the space between the rib members themselves, so that when the ribs of the adjacent section are in position the spaces between the series of ribs will be practically the same.

In the construction of the bolster-frame its length when the sections are telescoped will be equal to that of the width of a single bed and when extended to their limit to the width of a double bed, it being understood that the lapped portions—that is, those portions located between the center bands—are to be of sufficient length to give the requisite rigidity to the structure.

In Fig. 4 I have shown a modified form of construction for assembling two sections. In this instance there is but one center band 5, and the ribs 3 of both sections have a sliding connection with the flutes of the inner plate 6. It will only be necessary in employing this form of center band to make it of, say, double or a little more the width of the two center bands shown in Fig. 1 to impart the requisite strength and rigidity to the structure. Where the parts are assembled under the construction shown in Fig. 4, the telescopic operation is the same as that shown in the structure illustrated in Fig. 1.

The bolster-frame made in the manner described will, by reason of its circular fluted end and center bands, be of sufficient rigidity to obviate the necessity of stuffing or filling the frame with cotton or the like, such as is usually done, so that the device will be exceedingly light, and thus easily handled. By reason of the fact that it is made wholly of metal it will be cleanly and will not be liable to harbor vermin, and being of open-work structure may, if the necessity arises, be easily and thoroughly cleansed.

The metals used in the construction of the device will be a matter of choice, and the particular manner of assembling the parts will be one of mechanical skill, having for its object simplicity of construction and durability in use. It will be obvious that the parts may be associated in other ways than that described, and for this reason I wish it to be understood distinctly that I do not limit myself to the features of assembling of the parts and to the exact manner in which the parts are constructed as herein set forth.

From the foregoing it is thought that the construction, operation, and many advan-

tages of the herein-described invention will be apparent to those skilled in the art without further description, and it will be understood that various changes in the size, shape, proportion, and minor details of construction may be resorted to without departing from the spirit or sacrificing any of the advantages of the invention.

What I claim is—

1. A sham-bolster frame, comprising opposite telescopic sections, each section having an outer substantially circular band, and substantially parallel ribs carried by and projected in the same direction from the band to form a skeleton substantially cylindrical section, the inner ends of the sections being overlapped, and a guide-band slidably embracing all of the rods at the overlapped portions thereof.

2. A sham-bolster frame, comprising opposite telescopic sections, each section having an outer substantially circular band, and a plurality of return-bend ribs, which have their opposite ends connected to the band and projected therefrom in the same direction to form a substantially cylindrical skeleton section, the outer ends of the sections being overlapped, and a band slidably embracing all of the rods at the overlapped portions of the sections.

3. A sham-bolster frame, comprising opposite telescopic sections, each of which is substantially cylindrical in shape and formed by separate longitudinal ribs, and a substantially circular band embracing the outer ends thereof, the band being folded longitudinally and embracing the ends of the rods, and a substantially circular band slidably embracing the inner overlapped portions of the sections.

4. A sham-bolster frame comprising two sections having a telescopic connection with each other, each section comprising a plurality of return-bend ribs, an end band held against lateral movement by beading the metal of the band around the ends of the ribs, and a center band comprising an inner and an outer plate, the inner plate being formed with grooves or beads in which the ribs slide when the sections are telescoped.

5. A sham-bolster frame comprising two sections having telescopic connection with each other, each section comprising a plurality of return-bend ribs, and an end band in which the ends of the ribs are housed and are held against lateral movement by beading the metal of the band around the ends of the ribs, and a center band comprising two pieces of metal the outer one of which is plain, and the inner one provided with beads or openings in which the ribs work when the frame is telescoped.

6. A sham-bolster frame, comprising opposite substantially cylindrical skeleton telescoped sections, each section comprising a plurality of cylindrically-arranged ribs, and

a band connecting the outer ends of the ribs, the inner ends of the sections being overlapped, and a band slidably embracing all of the overlapped ribs, and formed by outer and 5 inner band-sections, the inner section being provided with transverse grooves or beads slidably receiving the respective ribs.

In testimony that I claim the foregoing as my own I have hereto affixed my signature in the presence of two witnesses.

LEONTINA GULLY.
